DRINKING CUP

John Robinson Hare, Niagara Falls, N. Y.

Application July 6, 1951, Serial No. 15,776

Term of patent 7 years

(Cl. D44—9)

To all whom it may concern:

Be it known that I, John Robinson Hare, a citizen of the United States of America, residing at Niagara Falls, county of Niagara, State of New York, have invented a new, original, and ornamental Design for Drinking Cup, of which the following is a specification, reference being had to the accompanying drawings, forming a part hereof.

Figure 1 is a side elevation view of a drinking cup, showing my new design.

Figure 2 is a rear elevation view of the drinking cup, shown in Figure 1.

Figure 3 is a top plan view of the drinking cup, shown in Figures 1 and 2.

Figure 4 is a bottom view of the drinking cup, illustrated in Figures 1-3.

The dominant feature of my design resides in the handle portion of the drinking cup shown in full lines.

I claim:

The ornamental design for a drinking cup, substantially as shown and described.

JOHN ROBINSON HARE.
